UNITED STATES PATENT OFFICE.

EDWARD H. ULLNER, OF WEST NEW YORK, NEW JERSEY.

WINDOW.

1,116,767.

Specification of Letters Patent. Patented Nov. 10, 1914.

Application filed July 31, 1913. Serial No. 782,384.

To all whom it may concern:

Be it known that I, EDWARD H. ULLNER, of West New York, in the county of Hudson and State of New Jersey, have invented 5 certain new and useful Improvements in Windows, of which the following is a specification.

My invention relates more particularly to that class of windows which are provided with a pivotal sash frame.

Among other novel features which my invention includes are the following:— While it is not new to support a window sash frame on pivotal bearings instead of 15 a hinge so that it will swing inward laterally, it is new to provide pivotal bearings, which may be adjustably engaged or detached so that the sash frame may be removed from the main frame at will, and 20 these novel features are included within my invention.

At the lower corner of the sash frame, I provide a pintle, with a projecting pin by which it may be lifted from its socket; 25 while at the upper corner is a similar pintle, carrying a similar pin. The upper pintle is retained in operative position by a removable block, which normally sustains the pintle in place but when the block 30 is removed the pintle drops down, releasing the sash frame.

Having thus described some of the novel features comprised within my invention, I now more particularly describe and specify 35 the same by reference to the accompanying drawings which are illustrative sketches and in which similar letters and ordinals indicate identical parts.

Figure 1 is a front elevation of a window constructed in accordance with my invention, with parts thereof in section. Fig. 2 is an enlarged view showing the upper pintle retracted. Fig. 3 is a horizontal sectional view thereof taken through the upper 45 pintle.

Referring to the accompanying drawing by similar characters of reference throughout the several views, the numeral 4 designates generally my improved window which 50 consists of a window frame comprising the vertical side members 5 and upper and lower horizontal members 6 and 7. The upper and lower windows 8 and 9 are slideable in the removable frame 10, one side 55 of which is provided at its opposite ends

with sockets 11 opening inwardly through the side of the frame 10, as shown at 12, and for the purpose to be later explained. Upper and lower pintles 13 and 14 are 60 slideable in the sockets 11 and each is provided with a lateral extension 15 forming a finger grip by means of which said pintles can be operated. A removable block 16 is located in the lower end of the upper socket to engage the underside of the pintle 65 13 for retaining the same in its extended position, while concealing these said pintles 13 and 14 is a removable strip 17 secured to the inner side of the frame 10 at one side thereof. The pintles 13 and 14 when in 70 their extended positions engage the recesses 18 and 19 formed, respectively, in the horizontal members 6 and 7 of the window frame above referred to, obviously pivotally supporting the frame 10 and providing for 75 its removal upon the removal of the block 16 and the retraction of said pintles 13 and 14 which are operated by grasping the lateral extensions 15 in the fingers and sliding the same inwardly through the openings 80 12. From the foregoing it will be manifest that a window is provided which will fulfil all the requirements of such a device.

Having thus specified, shown and described the same I claim as novel and my 85 invention:

The combination of a window having sockets formed therein, a swinging frame mounted in the window frame and being provided with recesses, pintles slideable in 90 the recesses in the swinging frame into and out of engagement with the sockets in the window frame, whereby the sash will be swingingly mounted in said window frame, a block insertible in one of the recesses for 95 engagement with the corresponding pintle and retaining the latter in its respective socket, and a removable strip carried by the swinging frame and engaging one side thereof for concealing said pintles and retaining the block against displacement and also preventing displacement of said pintles.

Signed at borough of Manhattan, city and county of New York and State of New 105 York this 18th day of July, A. D. 1913.

EDWARD H. ULLNER.
